UNITED STATES PATENT OFFICE.

ROBERT W. SCOTT, OF PHILADELPHIA, PENNSYLVANIA, ASSIGNOR OF ONE-HALF TO LOUIS N. D. WILLIAMS, OF OGONTZ, PENNSYLVANIA.

KNITTED HOSIERY.

No. 893,663.

Specification of Letters Patent.

Patented July 21, 1908.

Application filed March 30, 1904. Serial No. 200,833.

To all whom it may concern:

Be it known that I, ROBERT W. SCOTT, a citizen of the United States, residing in Philadelphia, Pennsylvania, have invented certain Improvements in Knitted Hosiery, of which the following is a specification.

The object of my invention is to provide a shaped or fashioned sock or stocking which can be made in a simpler and cheaper manner than usual, the preferred form of the stocking being susceptible of manufacture by a continuous operation which produces a tubular web, upon either a flat or a circular machine, the web in the latter case being formed by rotating knitting instead of by reciprocating knitting, such as is usually resorted to in the manufacture of fashioned stockings. By making the stocking, or rather the blank of which the stocking is to be formed, upon one machine, I avoid all expensive transfer operations such as are necessary when more than one machine is employed in the fabrication of the stocking blank.

In the accompanying drawings, Figure 1, is a view of the foot and part of the leg of a stocking made in accordance with my invention. Fig. 2, is a view of the blank from which the stocking is made. Figs. 3 to 8 inclusive, are needle diagrams illustrating the method of knitting said blank, Figs. 9 and 10, are views illustrating certain modifications in the production of the heel portion of the stocking in accordance with my invention, and Fig. 11 is a view illustrating the needles of a modified form of machine upon which the sock or stocking can be knitted.

It may be well to state at the outset, that in knitting a so-called full-fashioned stocking it is customary to commence the knitting at the widest portion of the leg, the knitting being performed upon flat machines having spring-beard needles and the strip being knitted of a uniform width until the calf portion is reached, whereupon the strip is narrowed by the transferring of stitches from the end needles on both sides of the machine toward the center of the fabric until said fabric has been sufficiently narrowed for the ankle portion of the stocking, the latter being then knitted of uniform width until the formation of the heel is necessary. At this juncture, two yarn guides are thrown into action, one employed for knitting a projecting heel piece at one side of the ankle web, and the other for knitting a correspond-

ing heel piece at the opposite side of said ankle web, the intervening needles of the machine having the stitches cast from them.

The heel strips are knitted of uniform width down to the point where the rounding of the heel is to be effected, whereupon each of the strips is narrowed to the desired extent by transferring the stitches from needle to needle in the same manner as when narrowing for the calf portion of the stocking. When the knitting of the heel strips has been completed, they are cast from the needles and the selvaged inner edges of the heel strips are run upon the outermost needles of a separate machine, known as a footing machine, the intermediate needles of this machine receiving the loops around the instep portion of the leg web which were thrown from the needles of the leg machine when the formation of the heel strips was begun. The foot web is then knitted upon the needles of the second machine, the web being narrowed at each side to form the desired instep gussets, and being also narrowed at the toe so as to properly round the same. This method of manufacture is a slow and tedious operation, necessitating the use of expensive machinery and the highest class of skilled labor to operate it.

The main aim of my invention has been to so form the stocking as to permit of the use, in its production, of a web produced by tubular knitting preferably upon a high speed circular or rotating machine in place of the usual low speed reciprocating machine, and to effect the desired shaping or fashioning of the web without the necessity of using transfer points for transferring stitches from needle to needle or filling-up points for transferring a previously formed stitch of the knitted web to a naked needle, for the use of such transfer or filling-up points further reduces the production of the machine, since the knitting operation must be arrested while such points are in operation.

Referring, first, to Figs. 1 to 8 of the drawings, it will be observed that the stocking illustrated in Fig. 1, is very similar to an ordinary full-fashioned stocking, having a shaped calf 1, a square heel 3, with rounded lower corner 4, instep gussets 5, a seam 6 across the front of the toe, a seam 7 where the front of each heel strip is united to the rear end of the sole portion of the foot, and a seam 8 extending from the point of the toe around un-

derneath the foot and heel, up around the corner of the heel, and up along the back of the leg. In my improved stocking, however, the leg portion and the foot portion are not made separately, the stocking being produced from a web or blank of the character shown in Fig. 2, and this web being made in a manner which will be understood on reference to Figs. 3 to 8 inclusive.

10 It will be noted, on reference to Fig. 2, that the web has, at each edge of the same, bordering wales 2, which, when the web has been folded and seamed or sewed together to form the stocking, extend throughout the under-
15 side of the toe, the sole of the foot, and the rear of the heel, ankle, calf and leg of the stocking. In its preferable form, the fashioning or shaping of the different parts of the stocking is effected by a widening operation, 20 the various widening wales being introduced between the standing wales of the fabric and the bordering wales. The knitting of the fabric is by preference a rotary machine with a pair of needle-carrying segments movable from and towards each other around a full or interrupted circle of needles in a cylinder, the latter needles 10 (represented by the circular series of dots in Figs. 3 to 8,) forming the standing wales and the widening wales of the fabric, and the segment needles 11 forming the bordering wales of the fabric. A machine of this character is shown in my Patent No. 607,002, dated July 5, 1898. The machine knits round and round, a limited portion only of the needles 10 being in action at the beginning of the operation, and these needles being flanked by the bordering needles 11, the knitting yarn being carried across from one set of needles 11 to the other, and the floating yarns or elongated sinker wales being subsequently severed or trimmed off, either by automatic means or by hand, 40 with the result that, in either case, sinker wales or ends of yarn project from the bordering wales, as shown at 12, in Fig. 2, hence a characteristic feature of the stocking or blank, is that the outer edges, along the bordering wales, are ui selvaged.

45 In starting the knitting operation, only the needles 10 from *a* to *a* Fig. 3, may be in operation so as to produce a narrow web such as shown at *a* in Fig. 2, with bordering wales 2 at each side of the same produced upon the needles 11. As the knitting proceeds, however, these needles 11 are racked apart and needles 10 are successively brought into action at each end of the set of needles *a*—*a* 50 until the full amount of widening for the toe has been effected, as indicated at *b* in Fig. 2, by which time the relation of the needles 11 to the needles 10 will be that represented in Fig. 4, the needles 10 from *b* to *b* being in action. The widening wales are preferably in-

roduced in such manner as to prevent the formation of eyelet holes, as shown for instance in my Patent No. 614,349, dated November 15, 1898. The knitting of a web of uniform width for the foot of the stocking now proceeds until the point *d* is reached, whereupon there is a further introduction of needles 10 and racking out of the needles 11 for the purpose of producing the instep gussets 5, this widening operation proceeding until the web reaches the line *e*, Fig. 2, by which time the needles 11 bear the relation to the needles 10 shown in Fig. 5, the needles 10 from *e* to *e* being in action. The needles 10 from *c* to *c*, Fig. 5, are now put out of action but permitted to retain their stitches, and a few courses of stitches are knitted on each set of needles 10 from *c* to *e* and on the needles 11, these courses of stitches, shown at *k* in Fig. 2, being spaced apart to the extent of the width of the set of needles *c*—*c* and being independent of each other, save only as they may be connected by the floating yarns or elongated sinker wales extending from strip to strip. The needles 10 from *d* to *e*, Fig. 6, are then caused to cast their stitches, and the needles 11 are racked in to the position shown in Fig. 6, these segment needles also retaining their stitches. Knitting now takes place, therefore, only upon the needles 10 from *c* to *d* and on the segment needles the result being the production of two webs or strips separated to the extent of the needles *c*—*c*, and disconnected except as above set forth. The spaced webs or strips thus produced are intended to constitute the heel of the stocking, and each strip is gradually widened by racking out the needles 11 and bringing in needle after needle 10 outside of *d* until the desired shaping of the web for the corner of the heel has been accomplished, say until the needles from *d* to *f* have been again brought into action as shown in Fig. 7. The knitting of spaced webs of uniform width then proceeds until strips of the desired length for the heel have been produced, whereupon the central or instep set of needles 10 extending from *c* to *c*, is brought into action again and the knitting of web for the ankle portion of the stocking is proceeded with.

The purpose of casting the stitches from certain of the needles 10 and racking in the needles 11 before beginning to knit the heel webs, is to effect the narrowing of the ankle portion of the stocking, it being desirable that this portion of the stocking shall not be of as large diameter as the gusseted or widened rear portion of the foot of the stocking. The stitches are not cast off of the needles, 125 however, because it is objectionable to start the knitting upon naked needles, that is to say, needles which do not carry loops upon them. Of course, if the narrowing of the ankle in respect to the gusseted portion of 130

the foot is not desired, the retiring of the needles 10 from *d* to *e* and the racking in of the needles 11 before beginning the knitting of the spaced heel strips, need not be resorted to. After the knitting has been carried to the point *h* Fig. 2, needles 10 are successively brought into action at each end of the active set outside of the points *f* and the needles 11 are racked apart until the desired 10 widening for the calf portion of the leg has been effected as shown at *i*, Fig. 2, the needles 11 now bearing relation to the needles 10 shown in Fig. 8, and the needles 10 from *i* to *i* being in action. Knitting upon the 15 needles 10 from *i* to *i* and upon the needles 11 is then continued until the desired length of fabric for the leg of the stocking has been produced, whereupon all of the needles 10 from *i* to *a* at each end of the set are caused 20 to cast their stitches and are put out of action, the needles 11 are racked in to the points *a*, *a*, and the starting of a new stocking at the toe is begun and continued in the manner before described.

25 After the completion of the stocking blank in the manner described, the same is cut through the strips *k* so as to free the bottom of each heel strip from connection with the foot and ankle web, and the seaming up of 30 the stocking in the manner indicated in Fig. 1, is then effected. The strips *k* facilitate the union of the rear ends of the sole portion of the stocking and the front portions of the heel-strips, and to insure the cutting of said 35 strips *k* in a straight line, it is preferable to form a slack course in each of the same during the knitting operation.

Instead of forming the spaced heel strips 3 as parts of a continuous web in the manner 40 described, all of the stitches may, after knitting the web to the point *e*, Fig. 2, be cast off of the needles 10 from *c* to *e* Fig. 6, and from the needles 11, and the latter may then be 45 racked in to the position shown in Fig. 6, the needles 10 from *d* to *e* being retired, and the needles 10 from *c* to *c* being also retired but permitted to retain their stitches. The knitting 50 of fresh webs upon the needles 10 from *c* to *d* and upon the needles 11 may then be started, these webs being widened to shape the lower 55 corner of the heel, and the knitting being then continued until spaced strips of the desired length for the heel have been produced, whereupon the needles 10 from *c* to *c*, which 60 retained their stitches, may be brought into action again and the knitting of the ankle web proceeded with, the effect of this method of operation being the production of a web 65 of the character shown in Fig. 9. This method of manufacture, requires the knitting operation for the production of the spaced heel webs to be started upon naked needles and therefore necessitates the use of some form of web holder for retaining the 70 first course produced. Another method of

forming the heel is as follows: After the knitting of the foot web has been completed and the needles 10 from *c* to *c*, Fig. 6, have been thrown out of action, but permitted to retain their stitches, the knitting is proceeded with 70 upon the needles 10 from *c* to *e*, Fig. 5, and upon the needles 11, the knitting yarn floating from *c* to *c*, so as to produce two short webs such as shown in Fig. 10 for instance, similar to the webs *k* before referred to, after 75 which the needles 10 from *c* to *c* are brought into action again and the knitting of the ankle web is proceeded with. The webs *k* are subsequently severed along the central line (preferably marked by a slack course) 80 and the flaps which are connected with the ankle portion of the stocking, are run upon the needles of a separate machine whereby the heel strips 3 are produced, the flaps which are connected to the sole portions of 85 the foot web being run upon the needles of the machine whereby said sole portions are connected to the front edges of the heel strips.

It will be noticed on reference to Figs. 1 90 and 2, that the fashioning of the toe is effected by a single group of parallel shaping wales on each side of the foot, these shaping wales being interposed between the standing wales at the top of the foot and the bordering 95 wales at the bottom of the foot, and being introduced in quick succession, so as to impart the desired sharp rounding of the toe, all of the shaping wales of each group running to or starting from the bordering wales 2 at 100 the bottom of the foot, and this, I believe to be a novel construction, whether the web of which the foot is composed is produced by round and round knitting or by to and fro knitting, and in a separate application Serial 105 No. 203,709, I have broadly claimed the same.

It will be evident that a stocking such as I have shown in Fig. 1, can be produced by tubular knitting and by a continuous operation, hence, the speedy production of the stocking is insured, while the fact that it is a relatively easy task to render automatic the machine for the production of the stockings, lessens the labor cost of the stocking and thus adds this advantage to the rapidity of production. The term tubular knitting applies as well to the operation of a circular machine, and to the operation of that class of machines having opposite straight needle beds, and a yarn guide traveling up one side of the machine and down the other, and crossing at the ends of the needle beds, and in Fig. 11, I have shown the use of bordering 110 needles in connection with such a machine. While in the operation of this machine reciprocation of the yarn guides is resorted to, instead of round and round knitting as in the circular machine the comparative slowness 115 of this method may be counteracted to a 120

great extent by the use of a plurality of yarn guides, and the shortness of the sinker wales between the two sets of bordering wales, reduces waste of yarn to a minimum.

5. Although I prefer, in carrying out my invention, to start the knitting of the stocking web at the toe and to fashion the web by widening in the manner described, my invention may be carried out by a reversal of 10 such process, that is to say, the web may be started in the leg portion by knitting upon the needles 10 from *i* to *i* (Fig. 8) and upon the needles 11, and then narrowed at the 15 calf by throwing out of action successively the needles 10 from *i* to *e* (Fig. 8) and racking in the needles 11 to form the ankle portion of the stocking, upon the completion of which the needles 10 from *c* to *c* (Fig. 8) may be thrown out of action, but permitted to 20 retain their stitches, and the spaced heel webs may be produced upon the needles 10 from *c* to *e* and upon the needles 11, narrowing from *e* to *d* towards the completion of the heel webs to shape the corner of the heel, where- 25 upon needles 10 from *e* to *e* may be brought into action and the knitting of the foot portion of the stocking may be proceeded with, narrowing being resorted to to form the in- 30 step gussets 5, (Fig. 1) and to effect the rounding of the toe, upon the completion of which latter operation the needles 11 may be racked apart to their full extent and the needles 10 from *i* to *i* brought into action so as to start the production of another stocking 35 leg, some form of web holder being em- ployed in order to permit of the starting of the knitting upon naked needles.

The bordering wales 2 at the opposite edges of the stocking blank shown in Fig. 2, 40 are uniform in width throughout the web, these wales being formed upon the needles 11, which it is desirable to retain in action at all times. In the finished stocking, however, these wales may be reduced in width by 45 the trimming and sewing operations, it being desirable to have fewer bordering wales in the finished stocking than in the blank.

The machine may, if desired, be provided with a plurality of yarn feeds, for the purpose of facilitating production or permitting the use of yarns of different color or material in the stocking when desired.

If desired, the leg portion of the stocking may be a tubular seamless web. In such 55 case the final adjustment of the needles 11, on the completion of the widening for the calf of the stocking, will close the gap between said needles. The width of the central band of standing wales *a* of the stocking 60 blank, is preferably twice the width of each of the groups of bordering wales, so that when the blank is folded, the standing wales on the top of the toe will equal the width of the two sets of bordering wales, and thus pro- 65 vide for the proper formation of the seam 6

across the toe. The heel strips may be formed with selvages on those edges which are afterwards to be joined to the rear ends of the sole webs of the stocking by reciprocating the yarn guide during the formation 70 of the heel webs, the change in the direction of motion taking place at the front of the machine when the guide is in line with the inactive needles 10 between the points *c*, *c*, in fact, various forms of heels and toes fash- 75 ioned by shaping wales at each side, may be used in connection with my invention, hence some of the claims which I have based upon my invention are not limited to the specific forms of toe and heel which I have illustrated, 80 although these are preferred.

By the term rectangular heel, or heel web as used in some of the claims, I mean a heel or heel web in which the wales form downward continuations of the wales in the rear 85 portion of the ankle. Such heel, may, and usually does, have its corner shaped or rounded, either by means of wales introduced or dropped in the knitting operation as described, or by subsequent trimming, as 90 during the seaming operation.

Where in the claims I use the term "fashioned" such term applies to a fashioning produced by the introduction of shaping wales during the knitting operation, and is distinct 95 from a mere shaping or fashioning of a knitted web by cutting the same.

In the production of half hose, or hose with ribbed legs, the production of a fashioned calf being unnecessary, the ankle portion of the web will be knitted of such length as may be necessary for the subsequent attachment thereto of a ribbed top or a ribbed leg, the fact that such ankle web is flat permitting the use of a flat ribbed web for the top or leg 100 of the stocking, and the employment of an ordinary flat or straight looping machine, instead of the special circular machines which have to be employed in looping ribbed tops or legs to seamless tubular webs. By the 105 term "one piece web" as used in some of the claims, I mean a web in which the heel portions are knitted in one piece with, and of the same yarn or yarns as, the leg, ankle, and foot portions.

Having thus described my invention, I claim and desire to secure by Letters Patent,

1. A sock or stocking, having a foot with fashioned toe, and a rectangular heel with fashioned corner, the whole comprising a one-piece web, fashioned in each part by widening wales, and having unselvaged edges seamed along the bottom of the foot.

2. A sock or stocking, having a foot with fashioned toe, and a rectangular heel with fashioned corner, the whole comprising a one-piece web, fashioned in each part by widening wales, and having unselvaged edges seamed along the bottom of the foot and in the rear 125 of the heel.

3. A stocking, having a foot with fashioned toe, a fashioned calf, and a rectangular heel with fashioned corner, the whole comprising a one-piece web fashioned in each part by widening wales, and having unselvaged edges secured along the bottom of the foot, and in the rear of the ankle and calf.

4. A stocking, having a foot with fashioned toe, a fashioned calf, and a rectangular heel with fashioned corner, the whole comprising a one-piece web fashioned in each part by widening wales, and having unselvaged edges secured along the bottom of the foot, in the rear of the heel and in the rear of the ankle and calf.

5. A sock or stocking, having bordering wales on each side of the center of the sole portion of the foot, and having shaping wales in each side of the foot, all of which shaping wales run to said bordering wales.

6. A sock or stocking, having bordering wales on each side of the center of the sole portion of the foot and having, in each side of the foot, widening wales, all of which start from said bordering wales.

7. The mode herein described of making a sock or stocking, said mode consisting in producing, by continuous rotary knitting and by a single continuous operation, a web comprising foot and leg portions, with intervening spaced heel portions, fashioning said web by shaping wales in the portions which require to be fashioned, severing connection between adjoining portions of the web, and seaming the unselvaged edges thereby produced and the edges of the heel webs.

8. The mode herein described of making a sock or stocking, said mode consisting in producing, by continuous rotary knitting and by a single continuous operation, a web comprising foot and leg portions, with intervening spaced heel portions, fashioning said web by widening wales in the portions which require to be fashioned, severing connection between adjoining portions of the web, and seaming the unselvaged edges thereby produced and the edges of the heel webs.

9. The mode herein described of making a sock or stocking, said mode consisting in producing, by continuous rotary knitting and by a single continuous operation, a web comprising foot and leg portions, with bordering wales and spaced heel portions, fashioning said web by shaping wales inside of the bordering wales, severing connection between adjoining bordering wales, and seaming the unselvaged edges thereby produced, and the edges of the heel webs.

10. The mode herein described of making a sock or stocking, said mode consisting in producing, by continuous rotary knitting and by a single continuous operation, a web comprising foot and leg portions, with bordering wales and spaced heel portions, fashioning said web by widening wales inside of the bor-

dering wales, severing connection between adjoining bordering wales, and seaming the unselvaged edges thereby produced and the edges of the heel webs.

11. The mode herein described of producing a sock or stocking web, said mode consisting in knitting a tube by a single continuous operation, starting at the toe with a narrow web having opposite bordering wales, widening by introducing wales inside of the bordering wales to shape the toe, continuing the knitting to form the foot, forming a pair of spaced heel webs, one on each side of a central group of retained stitches, and knitting onward from said heel webs and retained stitches to form the ankle.

12. The mode herein described of producing a stocking web, said mode consisting in knitting a tube by a single continuous operation, starting at the toe with a narrow web having opposite bordering wales, widening by introducing wales inside of the bordering wales to shape the toe, continuing the knitting to form the foot, forming a pair of spaced heel webs, one on each side of a central group of retained stitches, knitting onward from said heel webs and retained stitches to form the ankle, and introducing wales inside of the bordering wales to form the calf.

13. The mode herein described of producing a sock or stocking web, said mode consisting in knitting a tube by a single continuous operation, starting at the toe with a narrow web having opposite bordering wales, widening by introducing wales inside of the bordering wales to shape the toe, continuing the knitting to form the foot, dropping stitches within and adjacent to the bordering wales and shifting the latter correspondingly inward, knitting spaced heel webs, one on each side of a central group of retained stitches, and knitting onward from said heel webs and retained stitches to form the ankle.

14. The mode herein described of producing a stocking web, said mode consisting in knitting a tube by a single continuous operation, starting at the toe with a narrow web having opposite bordering wales, widening by introducing wales inside of the bordering wales to shape the toe, continuing the knitting to form the foot, dropping stitches within and adjacent to the bordering wales and shifting the latter correspondingly inward, knitting spaced heel strips, one on each side of a central group of retained stitches, knitting onward from said heel webs and retained stitches to form the ankle, and introducing wales inside of the bordering wales to form the calf.

15. The mode herein described of producing a sock or stocking, said mode consisting in knitting a tube by a single continuous operation, starting at the toe with a narrow web having opposite bordering wales, widening by introducing wales inside of the border-

ing wales to shape the toe, continuing the knitting to form the foot, forming a pair of spaced heel webs, one on each side of a central group of retained stitches, and knitting 5 onward from said heel webs and retained stitches to form the ankle, severing the web between the bordering wales, and seaming said unselvaged edges and the edges of the heel webs.

10 16. The mode herein described of producing a stocking, said mode consisting in knitting a tube by a single continuous operation, starting at the toe with a narrow web having opposite bordering wales widening by introducing wales inside of the bordering wales to shape the toe, continuing the knitting to form the foot, forming a pair of spaced heel webs, one on each side of a central group of retained stitches, knitting onward from said 15 heel webs and retained stitches to form the ankle, introducing wales inside of the bordering wales to form the calf, severing the web between the bordering wales, and seaming said unselvaged edges and the edges of the 20 heel webs.

17. The mode herein described of producing a sock or stocking, said mode consisting in knitting a tube by a single continuous operation, starting at the toe with a narrow 25 web having opposite bordering wales, widening by introducing wales inside the bordering wales to shape the toe, continuing the knitting to form the foot, dropping stitches within and adjacent to the bordering wales

and shifting the latter correspondingly inward, knitting spaced heel webs on opposite sides of a central group of retained stitches, knitting onward from said heel webs and retained stitches to form the ankle, severing the web between the bordering wales, and 35 seaming said unselvaged edges and the edges of the heel webs. 40

18. The mode herein described of producing a sock or stocking, said mode consisting in knitting a tube by a single continuous operation, starting at the toe with a narrow web having opposite bordering wales, widening by introducing wales inside the bordering wales, to shape the toe, continuing the knitting to form the foot, dropping stitches within and adjacent to the bordering wales and shifting the latter correspondingly inward, knitting spaced heel webs on opposite 45 sides of a central group of retained stitches, knitting onward from said heel webs and retained stitches to form the ankle, widening by introducing wales, inside of the bordering wales, to form the calf, severing the web between the bordering wales, and seaming said unselvaged edges and the edges of the heel 50 webs. 55

In testimony whereof, I have signed my name to this specification, in the presence of two subscribing witnesses.
